UNITED STATES PATENT OFFICE.

JOSEPH VAN HOUTEN AND WILLIAM H. VAN HOUTEN, OF NAPLES, N. Y.

HORSESHOEING-STAND.

SPECIFICATION forming part of Letters Patent No. 241,896, dated May 24, 1881.

Application filed March 25, 1881. (Model.)

To all whom it may concern:

Be it known that we, JOSEPH VAN HOUTEN and WM. H. VAN HOUTEN, of Naples, in the county of Ontario and State of New York, have 5 invented certain new and useful Improvements in Horseshoeing-Stands; and we do hereby declare that the following is a full, clear, and exact description of the invention, which will enable others skilled in the art to which it applies to make and use the same, reference being had to the accompanying drawings, which form a part of this specification.

Figure 1 is a top view. Fig. 2 is a side view. Fig. 3 is a vertical sectional view, and Fig. 4 is a detail sectional view.

Corresponding parts in the several figures are denoted by like letters of reference.

This invention relates to an improved stand for the use of blacksmiths in shoeing horses; 20 and it consists in certain improvements in the construction of the same, which will be hereinafter fully described, and particularly pointed out in the claims.

In the drawings hereto annexed, A represents a nut held between the upper ends of three (or more) curved standards, B B, the lower ends of which are fixed in a ring or frame, C.

D is a threaded rod, vertically adjustable in 30 the nut A, and carrying at its upper end a flat semi-oval plate, E, and a curved rest, F, either of which, or the latter of which, may be removed while the other one is being used.

G is a band or brace, adjusted around the 35 standards B and serving to strengthen these, forming at the same time the rim of the tool-tray. The latter consists of a properly-shaped

plate, H, formed with hooks I, by which it is secured upon the rim G, as shown. Swinging drawers or boxes J are pivoted under the bottom of the tray to hold horseshoe-nails.

In operation the foot of the horse is rested in the curved rest F while the hoof is being pared and the shoe nailed on. While the nails are being clinched or unclinched the foot rests 45 upon the plate E. The rests may be readily adjusted to the proper height by raising or lowering the threaded rod D in nut A. While at work the operator places his feet upon the ring or frame C to prevent the stand from being overturned. When the said frame C is circular in form, as shown, the stand may be 50 easily tilted and rolled into or out of the shop.

Having thus described our invention, we claim and desire to secure by Letters Patent 55 of the United States—

1. In a horseshoeing-stand, the combination of the ring or frame C, standards B, plate H, nut A, and vertically-adjustable rod D, having semi-oval plate E and curved rest F, substantially as and for the purpose set forth.

2. In a horseshoeing-stand, the combination, with the standards B, of the rim or band G, and the plate H, having or formed with hooks I, substantially as herein described, for 60 65 the purpose set forth.

In testimony that we claim the foregoing as our own we have hereto affixed our signatures in presence of two witnesses.

JOSEPH VAN HOUTEN.

WILLIAM HENRY VAN HOUTEN.
